Primary Examiner — Samantha Wood*Assistant Examiner* — Aula Soroush(74) *Attorney, Agent, or Firm* — Woodard, Emhardt, Henry, Reeves & Wagner, LLP(57) **CLAIM**

The ornamental design for a dog balance platform, as shown and described.

DESCRIPTION

FIG. 1 is a top right perspective view of the dog balance platform showing my new design;

FIG. 2 is a top left perspective view thereof;

FIG. 3 is a bottom right perspective view thereof;

FIG. 4 is a bottom left perspective view thereof;

FIG. 5 is a top plan view thereof;

FIG. 6 is a front view thereof;

FIG. 7 is a right view thereof;

FIG. 8 is a left view thereof;

FIG. 9 is a bottom view thereof; and,

FIG. 10 is a back view thereof.

The broken lines illustrate portions of the dog balance platform and form no part of the claimed design.

1 Claim, 7 Drawing Sheets(56)
